GAMING CHUTE FOR DICE

John M. Claire, Astoria, N. Y.

Application August 13, 1954, Serial No. 31,854

Term of patent 7 years

(Cl. D34—5)

Fig. 1

Fig. 2 is a rear perspective view thereof; and
Fig. 3 is a side elevational view thereof.

I claim:

The ornamental design for a gaming chute for dice, substantially as shown.
